ELECTRIC CONTACT SNAP FASTENER

Otto J. Huelster, Waterbury, Conn., assignor to
 Scovill Manufacturing Company, Waterbury,
 Conn., a corporation of Connecticut

Application July 15, 1943, Serial No. 494,783

7 Claims. (Cl. 173—363)

1

This invention relates to snap fasteners and particularly one in which an electric contact is incorporated.

One object of this invention is to employ a conventional snap fastener device comprising a socket and a stud which may be used as a make and break switch in an electric circuit, and providing a spring contactor member to connect electrically the parts when in assembled position and always assure a positive electrical connection regardless of any vibrations, strains or tendency to separate to which the fastener connection may be subjected.

The invention finds one of its preferred embodiments in connection with aviators' uniforms that are provided with electrical heating elements to supply heat to the aviator at high altitudes, this device being used to detachably make the electric connection such as between the boots and the adjacent part of the garment and also between the glove and the sleeve of the garment or any other parts of the complete uniform that it is desired to electrically connect together. This particular fastener can also be advantageously used wherever any electric wires are desired to be detachably joined to complete and assure an electric circuit.

With the above noted and other objects in view, the invention consists in certain novel features of construction and combinations and arrangement of parts as will be more fully hereinafter set forth and pointed out in the claims.

Referring now to the drawings wherein—

Fig. 1 shows a side view of the socket and stud members of the snap fastener device shown in separated state;

Fig. 2 is a bottom plan view of the socket member;

Fig. 3 is a view of the socket and stud members in assembled position with the socket member in sectional elevation;

Fig. 4 is a side view of the contactor spring as it appears before the assembly to the socket;

Fig. 5 is a top plan view of the same;

Fig. 6 is a side view of a modified form of a contactor spring separated from the socket, and

Fig. 7 is a top plan view of the same.

Referring now to the drawing in which like reference numerals designate like parts throughout the several views, the numeral 10 designates generally a socket member and the numeral 11 a stud member. The socket member comprises a socket shell 12 having an enlarged hollow rim portion 12a within which is positioned a split spring ring 13. The shell 12 is also formed with

2

a domed portion 12b having an aperture 14 in its crown portion. Secured within the aperture 14 of the domed portion is a contactor spider spring 15. Specifically, the contactor spider spring 15 consists of a shoulder portion 15a which is provided with a central upstanding neck portion 16 terminating in a series of relatively large teeth 17 initially arranged in a cylindrical position. The neck portion 16 is adapted to be inserted through the aperture 14 to a position where the shoulder portion 15a seats against the adjacent surface of the domed portion 12b and whereupon the teeth 17 thereof are formed thereover as a means of rigidly securing the contactor spring 15 to the socket shell 12. The opposite portion of the spider spring 15 is formed into a series of reversely bent spring fingers 18 extending into the hollowed portion of the shell dome 12b.

20 The socket shell 12 with attached contactor spring 15 in turn is made secure to a dished disc part 19a of a wire terminal connector 19 as by means of an assembly eyelet 20. The eyelet 20 has a base flanged part 20a which overlies the terminal disc 19 and preferably is covered with a cap member 21 for the purpose of covering the opening in the eyelet and the blunt edge of the eyelet flange 20a as well as for appearance sake. The opposite end of the eyelet is adapted to be 25 spun over or upset against the interior of the contactor spring 15 in a manner as shown in Fig. 3 to hold all the parts rigidly secured together.

It is to be noted that by reason of the fact that the neck portion of the contactor spring 15 is 30 made in the form of teeth 17 the ends of said teeth after they are bent over into retaining position with the socket shell 12 are so disposed as to be adapted to embed into the interior surface of the dished disc part 19a of the wire terminal connector 19 as a means of providing a better 35 anchorage and electrical contact between said wire terminal connector 19 and the socket contactor spring 15 and also to preclude the terminal connector from turning relative to the socket member 10.

The stud member 11 is formed with the usual 40 bulbous shaped head portion 22 and integral base flange 23. The stud member 11 is also secured to the disc part 24a of a wire terminal connector 45 24 as by means of a rivet eyelet 25 upset within the head portion 22 of said stud member in the usual manner.

In assembling the stud 11 to the socket 10 the stud is inserted through an opening 26 in the 50 rim portion 12a of the socket 12, and the stud

head portion 22 is adapted to snap past the split ring 13 for detachable interlocking engagement with said socket. Under normal circumstances the stud connection with the socket member would be in relative loose manner, and therefore not suitable to conduct an electric current therethrough, but to assure that there will be no electrical break between the socket and the stud member under all circumstances the contactor spring 15 is secured into the socket as described above and the spring fingers 18 thereof are adapted to resiliently contact the entering end of the stud head 22 and thus maintain a positive electrical connection therewith.

Figs. 6 and 7 show a modified form of contactor spring 30 wherein the neck 31 may be made cylindrical and spun over about the aperture of the socket shell for securing the parts together. The spring member 30 has an intermediate domed portion 32 providing for a relatively flat shoulder 32a comparable to the shoulder portion 15a of Figs. 4 and 5. The domed portion 32 terminates in a flanged base 33, and out of this base is sheared a plurality of spring tongue members 34, three in this instance, that are arced downwardly out of the plane of the contactor base and adapted to engage the leading end of the stud head in a manner similar to the spider contactor spring 13 described in connection with the preferred construction of the invention.

In the objects it was stated that this fastener would find particular use in connection with electrically heated aviators' uniforms. In the drawing the fastener elements are shown unattached to any supporting structure except for the wire terminal connection. It is also within the preview of this invention to attach the fastener elements directly to that portion of the garment that is to be electrically connected to some adjacent part of the garment. This may be readily accomplished in connection with the socket member 19 by disposing the fabric between the eyelet flange 20a and the terminal disc 19a prior to the final assembly of the assembly eyelet 20 to its respective shall 12, and in connection with the stud member the fabric may similarly be disposed between the terminal disc 24a and the flange of the stud eyelet 25 prior to the final assembly of said eyelet to the stud member 11.

While there are herein described and shown in the drawings two illustrative embodiments of the invention, it is to be understood that the invention is not limited thereto, but may comprehend other constructional arrangements and details of parts without departing from the spirit of the invention.

I claim:

1. In a separable electric connector comprising conventional socket and stud members wherein said stud is adapted to enter into the socket by a direct thrust, spring ring means in said socket for snap locking engagement with said stud, said socket having an apertured closed end portion, a contactor member having a neck portion projecting through said aperture and upset against said closed end portion, and spring fingers integral with said contactor member for resiliently engaging the leading end of said stud when in assembled position.

2. In a separable electric connector comprising conventional socket and stud members wherein said stud is adapted to enter into the socket by a direct thrust, spring ring means in said socket for removable snap locking engagement with said stud, said socket having an apertured closed end

portion, a contactor member having a neck portion projecting through said aperture, a series of teeth forming the end portion of said neck, said teeth bent over against the outer surface of said closed end portion as a means for securing said contactor member to said socket, an apertured wire terminal connector of domed shape disposed upon the socket closed end portion and seated against the terminal ends of said teeth, a rivet member projecting through said terminal connector aperture and said connector neck and having one end upset to anchor said connector and socket together as a unit, and resilient means carried by said contactor for making an electric engagement with the head end of said stud when in assembled position.

3. In a separable electric connector comprising conventional socket and stud members wherein said stud is adapted to enter into the socket by a direct thrust, spring ring means in said socket for snap locking engagement with said stud, said socket having an apertured closed portion, a contactor member having a neck portion projecting through said aperture and upset against said closed portion, a wire terminal connector surmounted on said socket closed portion, a rivet eyelet securing said connector and socket with attached contactor member together as a unit, and resilient means formed as a part of said contactor for making an electric engagement with the head end of said stud when in assembled position.

4. A separable electric connector as defined by claim 3 wherein the neck of said contactor member terminates in a series of teeth that are upset over said closed portion to initially hold the socket and contactor members together.

5. A separable electric connector as defined by claim 3 wherein said contactor member comprises a shell having means for attachment to said socket and terminating in a transverse flanged base, and a series of arcuate resilient tongue members struck out of the flanged base for making an electric contact with the head end of said stud when in assembled position.

6. A separable electric connector as defined by claim 3 wherein said contactor member comprises a domed shell nested within the closed portion of said socket and having means for attachment to said socket, said contactor shell terminating in a radial flanged base having a series of tongue members sheared out of said flange and biased downwardly into a series of spring fingers that are adapted to make electric connection with the head end of said stud when in assembled position.

7. A socket member for an electrical connector, said socket member comprising a shell having a closed end with a central aperture and an open end provided with means for detachably receiving a stud member forming a component part of the electrical connector, a contactor member comprising an annular part formed with a central neck portion substantially normal to said annular part, said annular part seated against the inner face of the shell closed end with the projecting neck of said annular part fitted through said opening and upset against the opposite face of said closed end as a means of attaching the shell and contactor together as an integral unit, and spring means formed out of the annular part of said contactor for making electrical connection with the leading end of said stud when the latter is assembled to said socket.
